W. RINE.
TANK SIPHON.
APPLICATION FILED NOV. 3, 1919.

Patented Feb. 7, 1922.

UNITED STATES PATENT OFFICE.

WILLIAM RINE, OF PHILADELPHIA, PENNSYLVANIA.

TANK SIPHON.

1,406,080.

Specification of Letters Patent. Patented Feb. 7, 1922.

Application filed November 3, 1919. Serial No. 335,284.

To all whom it may concern:

Be it known that I, WILLIAM RINE, a citizen of the United States, residing at Philadelphia, in the county of Philadelphia and State of Pennsylvania, have invented new and useful Improvements in Tank Siphons, of which the following is a specification.

The invention relates to water distribution and more particularly to devices for controlling the flow or outflow of fluids from a tank or reservoir and has for an object to provide a siphon valve for siphoning a quantity of fluid from the fluid containing tank.

Among other features the invention comprehends a siphon valve which after being initially set in operation, will siphon a quantity of fluid from the tank and destroy the siphon when the level of the fluid in the tank reaches a certain point, various adjustments being provided for the adaptation of the valve to various forms and kinds of flush tank devices and appliances.

In the further disclosure of the invention, reference is to be had to the accompanying drawings, constituting a part of this specification in which similar characters of reference denote corresponding parts in all the views, and in which,

Figure 1— is a sectional view taken through a tank or reservoir showing my device applied thereto, parts being broken away and disclosed in section, to disclose the underlying structure.

Figure 2— is an end elevation.

Figure 3— is an enlarged horizontal sectional view taken on the line 3—3 in Figure 1.

Figure 4— is a perspective view of the lifting member.

Figure 5— is a fragmentary perspective view of the pull or handle and the adjusting elements.

Figure 6 is a detail view showing the swinging vane.

Referring more particularly to the views, I provide a tank 10 having a suitable inlet pipe 11 thereto, which is controlled by a valve 12 including a rod and ball structure 13, the latter being adapted to rise and fall with the level of the fluid 14 in the tank 10 to open or close the valve 12 as the case may be, thus determining the level of the fluid in the tank.

My particular device comprises a body 15

which is formed to provide a long leg 16 and a short leg 17, the latter being enlarged in cross sectional area to form a compartment 18, of a square configuration in cross section, whereas the long leg 16 is tubular and at its point of connection with the tank 10, registers with an outlet pipe 19.

A lifting member 20 is provided in the compartment 18 of the short leg 17 and it consists essentially of a horizontal square frame 21 upon which is pivoted at 21^a a vane 22, normally disposed in a horizontal position and reposing against a stop lug 23 struck from the frame 21, the upward swinging movement of the vane 22 being limited by a stop lug 24, projecting from a bail 25 forming a part of the frame 21. The vane 22, together with the frame 21 is adapted for vertical movement within the compartment 18 and normally tends to close the lower end of the compartment and which being filled with water, will result in the contents of the compartment being raised to pass into the long leg 16 when the lifting member 20 is actuated.

The lifting member includes a vertical stem 26 which preferably has a threaded portion 27, the lower end of the stem being rigidly secured to the bail 25 with a closure 28 threaded on to the threaded portion 27 and therefore adjustable vertically on the stem for a purpose that will be hereinafter more fully disclosed. The upper portion of the stem projects loosely through a vertical tubular guide 29 which is secured to the upper portion of the short leg 17 and depends within the compartment 18, the upper extremity of the stem 26 carrying a closure and stop element 30 which normally reposes upon the top of the guide 29, limiting the downward movement of the lifting member in the compartment 18 and also tightly fitting the top of the guide to act as a closure therefor. In a similar manner when the lifting member is pulled upwardly, the closure 28 bears against the lower depending end of the guide to close the same, the upper end of the guide at this time being open by reason of the raising of the stem 26. With this construction, one end of the guide 29 and what might also be termed a pipe, is closed when the lifting member is in its lowered position and the lower end of the pipe is closed when the lifting member is in its uppermost position.

Mounted to swing on a projecting stud 31 carried by the body 15, is an adjusting arm

32, intermediate portions of which are provided with cross apertures 33, the free extremity of the arm having connected thereto, one end of a rod 34, the upper end of which has connection with the closure and stop member 30 and mounted to swing on the tank 10 is a pull 35 which may be in the form of a handle or some other convenient device of a similar nature, said pull having 10 a rod 36 connected thereto and extending downwardly to have its lower end connect with the adjusting arm 32 through one of the apertures 33.

At substantially the juncture of the long leg 16 with the short leg 17, there is provided a depending pipe 37 which extends downwardly to within a short distance of the bottom of the tank, said pipe being provided to break the siphon as will be herein- 15 after set out in explaining the operation of the device.

Now assuming that the tank is filled with water 14, when it is desired to remove a quantity of the water from the tank to have the same flow through the outlet pipe 19, a pull is exerted on the pull handle 35, thus exerting an upward pull on the rod 36, and which in turn will cause the adjusting arm 32 to be swung upwardly thus raising 20 the lifting member 20 and the quantity of water contained in the compartment 18, with sufficient force to cause the water to flow upwardly around the curved portion at the juncture of the long and short leg 25 16, 17, and into the long leg 16 through which the water will flow to the outlet pipe 19, and as will be apparent a siphon will be created so that the water contained in 30 the tank will continue to flow up through the shortened leg 17 and down through the long leg 16, the upward flow of the water through the compartment 18 holding the vane 22 in a substantially open position. Now when the level of water in the tank 35 reaches a point below the lower end of the pipe 37, the inrush of air through the pipe 37 to the interior of the body 15, will break 40 the siphon, causing the vane 22 to return to its closed horizontal position, and the 45 valve 12 now being open because of the lower position of the ball float or rod and ball structure, a new supply of water will be received through the pipe 11, to again fill the tank to the required level. Now it 50 will be seen that when the device is in the 55 position shown in Figure 1, the closure 30

will close the upper end of the guide pipe 29, acting also as a stop to limit the downward movement of the lifting member and when an upward pull is exerted on the handle 35, the closure 28 engaging against the lower end of the guide pipe will close the same preventing any inrush of air through the guide pipe and which would tend to destroy the very suction which it is 60 65 desired to create in order to prolong the siphon.

By providing the adjusting arm 32 and the connection between the adjusting arm and the pull and between the adjusting arm and the lifting member, I allow for an adjustment of the connection between the pull and the arm because of the difference in the strokes of different forms of pull handles and thus it will be apparent that with my 70 75 form of device the same can be employed in connection with various kinds of operating levers or the like and an adjustment made between the operating lever or device and the lifting member whereby the 80 desired length of stroke to accomplish the desired purpose can be arranged for, through the medium of the adjusting arm having the cross apertures 33 for the accommodation of the lower end of the rod 36. 85

Although I have shown a particular form of my invention in the drawing and described the same in detail in this specification, it will be understood that various slight changes may be made from the construction set out without departing from the spirit of the invention, the scope of 90 which is defined in the appended claim.

Having described my invention, I claim—

A tank siphon comprising an inverted 95 U-shaped body including a long leg leading to an outlet and further including a short leg enlarged to define a chamber formed rectangular in cross-section, an open rectangular frame slidably mounted 100 within said chamber, a bail secured to said frame, a vertically swinging vane pivoted within said frame, stops for limiting upward and downward swinging of the vane, a tubular guide extending vertically within 105 said chamber, a stem slidable through said guide and connected with said bail, and members mounted on the stem above and below the guide and engageable therewith for limiting movement of the frame. 110

In testimony whereof I affix my signature.

WILLIAM RINE.
